CIRCUIT BREAKER

John G. Jackson and Wallace T. Allen, Detroit,
Mich., assignors to Square D Company, Detroit,
Mich., a corporation of Michigan

Application October 31, 1935, Serial No. 47,524

10 Claims. (Cl. 200—116)

This invention relates to automatic electric circuit breakers and has for its object the provision of an improved group circuit breaker.

Another object of this invention is to provide a sealable circuit breaker having a plurality of individual mechanisms, certain parts of which are made electrically common by a common bus.

Another object of this invention is to provide an electric circuit breaker having a plurality of individual mechanisms with a common bus supporting the stationary contact of each of the mechanisms.

Another object of this invention is to provide an improved and economical form of circuit breaker having a plurality of individual mechanisms and common mounting features.

Other objects and features of this invention will be readily apparent to those skilled in the art from the following specification and the appended drawings illustrating certain preferred embodiments of the invention in which:

Figure 1 is a top plan view of the circuit breaker apparatus according to the present invention with the outer cover broken away.

Figure 2 is a partial sectional view taken on the line II—II of Figure 1.

Figure 3 is a sectional view taken on the line III—III of Figure 1.

Figure 4 is a sectional view taken on the line IV—IV of Figure 3.

Figure 5 is a detail sectional view taken on the line V—V of Figure 3.

Figure 6 is a view similar to Figure 2 showing the parts in automatic trip position.

Figure 7 is a view similar to Figure 2 showing the parts in manual trip position.

Figure 8 is a view similar to Figure 2 showing the parts in resetting position.

Figure 9 is a partial sectional view showing a slightly modified form of construction.

Figure 10 is a partial sectional view showing a further modification.

The circuit breaker apparatus as illustrated comprises an outer sheet metal enclosing box 1 having an openable cover 2 hingedly or otherwise mounted thereon. Within this outer box is mounted one or more sealable circuit breaker units. In the specific embodiment illustrated there are shown two circuit breaker units sealably and supportably mounted upon a single plate which mounts them within the enclosing box. It is readily understood that any number of these units may be mounted upon a single sealing and supporting plate or that each unit

may have an individual sealing and supporting plate permitting separate manipulation of each separate unit. The outer box may be equipped with the usual knockouts, cover latch and similar features as is conventional in the art.

Each circuit breaker embodies a base 3 having a plurality of individual compartments 4. In each of these compartments is disposed an individual circuit breaker mechanism. Extending across the base in common with the individual compartments and mechanisms is a bus 5 secured to the base by means of the sealing rivet 6.

The dividing walls between the compartments are cut away to receive the bus 5 and a spacer 15 7 serves to rigidly mount the bus against the wall. The bus is provided with an enlarged opening receiving an insulating spacer 8 serving to insulate the rivet 6. At the back of the base is disposed an insulating fibre plate 9 which is 20 in turn backed up by the supporting and mounting plate 11. The rivet 6 extends through to the back of the plate 11 and hence mounts the parts together in sealable relationship.

The opening in the dividing walls between 25 the compartments is preferably enlarged to permit the gases generated by the rupture of an arc between any pair of contacts to be discharged within the entire circuit breaker interior and thus render less necessary any vent to 30 the outer air. These walls dividing the interiors into compartments are not at all essential and may be entirely omitted if desired.

The stationary contact 12 of each mechanism is conductively and resiliently supported upon 35 the bus 5 by means of a resilient arm 13. A woven conducting strip 14 may be used to interconnect the contact and bus to lower the resistance. Also supported on the bus is the base of a U-shaped latch 15. The ends of the strips 40 13 and 14 and the base 15 of the latch may be welded, riveted, or otherwise rigidly secured to the bus 5.

These elements at their points of connection are provided with an opening receiving the interior ends of a push button 16 in slidable and rotatable relation. The portion of the push button within this opening is provided with a peripheral groove 17 cooperating with a tongue 18 on the bus to limit the rotary movement of 45 the push button. A compression spring 19 disposed intermediate the bus 5 and the push button 16 is stressed to bias the push button outwardly and to rotate it in a counterclockwise direction to engage the tongue 18 with one side 50 55

of the peripheral groove 17. A pin 20 is provided at the lower end of the push button to limit its outward movement.

The push button is provided with a latching groove 21 adapted to be engaged by the ends 22 of the latch 15 to hold the push button inwardly against the bias of spring 19. Slidably mounted upon push button 16 is an insulating member 23 having a bimetallic strip 24 and movable contact 25 rigidly mounted thereon. The free end of the bimetal carries a conductor lug 26 and a latch pin 27. The latch pin 27 is loosely maintained in position at the end of the bimetal by holding strip 28 rigidly mounted thereon. The latch pin 27 extends through an opening in the member 23 and is received in a peripheral groove 29 in the push button 16. The pin 27 thus serves to latch the member 23 to the push button and provide for a common movement thereof as a unit.

20 An inclined notch 31 leads to the groove 29 at one point on the periphery of the push button and enables pin 27 to slide therein to release the latching engagement. A compression spring 32 biases member 23 away from the bus 5. The 25 member 23 is provided with surfaces 30 adapted to engage and separate the latch arms 22 when the member 23 moves upwardly under the bias of the spring 32.

A conducting strip 33 is disposed on a shelf on 30 the outside of each chamber and has a conductor lug 34 on one end thereof. A flexible lead 35 interconnects the conductor lugs 26 and 34. The conductor 33 is rigidly mounted on the base by riveting connection with a metallic insert 40 35 mounted in the base. This insert is interiorly threaded to receive the terminal stud 36.

The operation of an individual circuit breaker mechanism will now be described. The parts as shown in Figure 2 and at the bottom in Figure 3 40 are in their normal "on" position. Upon the occurrence of an overload the bimetallic strip 24 will warp clockwise pulling the pin 27 out of the groove 29 and permitting the member 23 to move upwardly under the bias of the compression 45 spring 32, thus carrying the movable contact 25 away from the stationary contact 12 in its upward movement. The surfaces 30 on the member 23 engage the arms of the U-shaped latch 15, moving them apart, thus unlatching the push button 50 16 and permitting it to move upwardly under the bias of its spring 19. The upward movement of the push button is limited by the pin 20 of the lower end thereof.

With the member 23 and the push button 16 55 both in their upward positions, the latch pin 27 will be again received within the groove 29 as soon as the bimetallic strip 24 is cool. The positions of the parts in the automatic trip position is shown in Figure 6 and at the top in Figure 3. 60 To reset the circuit breaker, the push button is pressed inwardly as shown in Figure 8 until the latch arms 22 engage the latching groove 21 on the push button, whereupon the contacts will be held in their engaged position. The resilient 65 mounting of the contact 12 by means of strip 13 is to insure adequate pressure between the cooperating contacts.

To manually trip the breaker, the push button 16 is rotated clockwise until the inclined notch 70 75 31 is brought over the pin 27, whereupon the member 23 is again free to move upwardly, separating, as it moves, the latch arms 22. The spring 19 then moves the push button outwardly and rotates it back to its original position whereupon the pin 27 and the groove 29 are again in

latching engagement. The limits of rotation of the push button are determined by the engagement of the tongue 18 with the groove 17.

With the breaker as herein illustrated, it is seen 5 that the stationary contacts are electrically connected together by means of the bus 5. In feeding through this breaker, one of the mechanisms will constitute a main circuit breaker through which the current will be led in to the bus 5. The remaining circuit breaker mechanisms will 10 constitute branch circuit breakers leading to separate circuits. This places a main and load breaker in series with any short circuit which may occur. In some instances it may be desirable 15 to extend the bus 5 to the exterior of the breaker and this construction has been illustrated in Figure 9 wherein the end of the bus 5 projects beyond the breaker and is provided with a terminal washer 37 and stud 38. The opening in the outer wall may be sealed by a tab 39 on the 20 fibre plate 9. In this embodiment the terminal on the bus 5 may serve either as a bus tap or as a main terminal for the breaker. When used as a main terminal all individual mechanisms will then function as individual branch circuit breakers 25 leading to separate circuits. When used as a bus tap one of the individual mechanisms will still function as a main circuit breaker leading to the bus 5 and the feeding through the individual mechanisms will be as in the preferred 30 embodiment. However, feeding from the bus tap 38 will only be through the main breaker to the bus 5.

In the modification shown in Figure 10 the 35 stationary contact 12 is directly and rigidly supported on the bus 5 and the movable contact 25 is supported as a resilient spring arm 41 mounted on the member 23. In this modification the spring arm 41 serves the same function as the spring strip 13 in maintaining an adequate pressure 40 between the cooperating contacts.

While the latch 15, the operating springs and the push button have all been shown as mounted upon and cooperating with the bus 5, it is obvious 45 that these parts may be carried by any supporting surface and that they have been here shown as cooperating with the bus for the purposes of simplicity, particularly in the embodiment illustrated.

In the appended claims the terms "box" and 50 "cover" are to be construed to include "cabinet" and "door" respectively.

While certain preferred embodiments of the invention have been specifically disclosed, it is understood that the invention is not limited 55 thereto as many variations will be readily apparent to those skilled in the art and the invention is to be given its broadest possible interpretation within the terms of the following claims:

What is claimed is:

1. Electric circuit breaker apparatus comprising 60 a plurality of aligned, spaced circuit breaker mechanisms including relatively movable contacts and means for automatically separating said contacts in response to overload, a common, elongated bus bar for said mechanisms having one contact of each mechanism conductively supported thereon in positions spaced along its length, and a sealable enclosure for said mechanisms and bus bar preventing access thereto. 65

2. An electric circuit breaker comprising a 70 unitary base having a plurality of aligned, spaced compartments therein, a circuit breaker mechanism mounted in each compartment and comprising relatively movable contacts and manual 75

and automatic means for separating said contacts, an elongated bus bar connected to said base and extending across said aligned compartments, one contact of each mechanism being conductively supported by said bus, and cover means for said compartments.

5. An electric circuit breaker comprising a unitary base having a plurality of aligned, spaced compartments therein, a circuit breaker mechanism mounted in each of said compartments and comprising relatively movable contacts and manual and automatic means for separating said contacts, an elongated bus bar connected to said base and extending across said aligned compartments, one contact of each mechanism being conductively supported by said bus, and a cover attachable to said base to form a sealable enclosure for said mechanisms and bus bar.

4. An electric circuit breaker comprising a plurality of individual mechanisms including stationary and movable contacts and means for automatically separating said contacts in response to overload, a common bus for said mechanisms, each stationary contact being resiliently 25 and conductively mounted on said bus in the path of its cooperative movable contact.

5. Electric circuit breaker apparatus, comprising a common conductor having a plurality of contact faces supported thereon, a unitary base 30 mounted over said conductor, said base having a plurality of compartments therein with one of said contact faces in each of said compartments, an individual automatic electric circuit breaker mechanism in each of said compartments and 35 including a movable contact adapted to cooperate with said contact face to perform the switching operation, and means for sealably closing said compartments.

6. Electric circuit breaker apparatus comprising a common conductor having a plurality of contact faces supported thereon, a unitary base mounted over said conductor, said base having a plurality of compartments therein with one of said contact faces in each of said compartments, an individual automatic electric circuit breaker mechanism in each of said compartments and including a movable contact adapted to cooperate with said contact face to perform the switching operation, insulating material in back of said conductor and connected to said base to substantially enclose the main portion of said conductor, and an extension on said conductor forming a terminal for connection of circuit wires leading current to said contact faces.

55. 7. Electric circuit breaker apparatus comprising a common conductor having a plurality of contact faces mounted thereon, a unitary base mounted over said conductor, said base having a plurality of compartments therein with one of 60 said contact faces in each of said compartments, an individual automatic electric circuit breaker mechanism in each of said compartments and

including a movable contact adapted to cooperate with said contact face to perform the switching operation, and a plate in back of said conductor and connected to said base, said conductor being maintained in position relative to the base by 5 the connection between said plate and base and by interengaging parts on said conductor and base.

8. Electric circuit breaker apparatus comprising a common conductor having a plurality of contact faces mounted thereon, a unitary base mounted over said conductor, said base having a plurality of compartments therein with one of said contact faces in each of said compartments, an individual automatic electric circuit breaker 10 mechanism in each of said compartments and including a movable contact adapted to cooperate with said contact face to perform the switching operation, interengaging surfaces on said conductor and said base limiting relative movement 15 therebetween except in one direction, and means preventing such relative movement in said one direction.

9. Electric circuit breaker apparatus comprising a common conductor having a plurality of contact faces mounted thereon, a unitary base mounted over said conductor, said base having a plurality of compartments therein with one of said contact faces in each of said compartments, an individual automatic electric circuit breaker 20 mechanism in each of said compartments and including a movable contact adapted to cooperate with said contact face to perform the switching operation, 25 interengaging surfaces on said conductor and said base limiting relative movement therebetween except in one direction, and means preventing such relative movement in said one direction.

10. Electric circuit breaker apparatus comprising a common conductor having a plurality of contact faces mounted thereon, a unitary base mounted over said conductor, said base having a plurality of compartments therein with one of said contact faces in each of said compartments, an individual automatic electric circuit breaker mechanism in each of said compartments and including a movable contact adapted to cooperate with said contact face to perform the switching operation, interengaging surfaces on said conductor and said base limiting relative movement 45 therebetween except in a direction at right angles to the plane of the conductor, and a plate in back of said conductor and connected to said base and preventing such movement while the plate and base are connected.

JOHN G. JACKSON.
WALLACE T. ALLEN.
